UNITED STATES PATENT OFFICE

GILBERT WAYNE RUGGLES, OF YOUNGSTOWN, OHIO

MECHANICAL STOKER

Application filed January 7, 1922. Serial No. 527,604.

The present invention, relating as indicated, to mechanical stokers, is directed to certain improved mechanical features for use in stokers, and more particularly, to one having both an underfeed and an overfeed section of grate area. A further object of the invention is the provision of means for such a stoker for more efficiently supplying the air and fuel to the grate area and for reducing the wear on the operating parts of the mechanism. To the accomplishment of the foregoing and related ends, said invention, then, consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings:—

Fig. 1 is a central vertical section through a single unit or retort forming part of my improved stoker; Fig. 2 shows a series of such units, some in front elevation and some in vertical transverse section, the first two units at the left being thus in elevation, the plane of the third unit being indicated by the line 30 *a—a*, Fig. 1, and the planes of the sections of the fourth, fifth and sixth units by the lines *b—b*, *c—c*, and *d—d*, respectively, Fig. 1; Fig. 3 is a plan view of two such units or retorts, showing the arrangement of the grates; Figs. 35 4 and 5 are longitudinal sectional views on a somewhat larger scale of the ram mechanism for feeding coal to the retort. Figure 4 being a section taken along the line 4—4 shown in Figure 6 looking in the direction of the arrows; and Fig. 6 is a partial cross section and end view of said ram mechanism taken along the line 6—6 shown in Figure 5.

In Fig. 1, there is shown, as indicated, but a single retort of a furnace between the front wall 1 and bridge wall 2 of which is mounted a mechanical stoker grate 3, composed of the usual plates and bars, and built upon a framework of steel forms. The grate area of this stoker is formed in several parts of 50 which the main part 4 is the underfeed sec-

tion to which the coal is supplied through a port 5 in the front wall 1, by means of a ram 6. This ram is in the form of a hollow box of rectangular cross-section and is reciprocated by means of connecting rod 7, through connections presently to be described, said rod being operated from the crank-shaft 8, that is mounted exteriorly of the stoker, and reciprocation of the same serving to force coal flowing into its path from the hopper 9 to the grate section 4. The ram 6 is mounted upon an adjustable wearing plate 10, and due to its rectangular form, it will be noted that such ram has a flat bottom and vertical sides, whereby all the wear is taken on the bottom of such adjustable plate. Accordingly, in order to take up for wear, and also to prevent sifting of fine coal, it is only necessary to place a shim or liner between such plate and its supporting frame, or if the plate becomes too thin, then to substitute a thicker plate. The plate 10 is illustrated in Fig. 1 as being supported directly beneath the reciprocating ram 6 through the engagement of its side edges with the top of spaced bars or beams 10a which form part of the rigid frame structure of the grate. Obviously screws (not shown) or other suitable fastening means may be utilized to removably secure the plate 10 in position so as to permit the removal thereof to effect the adjustments noted above. Mounted on said plate 10, so as to be adjustable longitudinally of the port 5 is a transverse bar 12 of triangular cross-section that provides the resistance necessary to cause the coal to properly pack.

Mounted in the forward end of the ram box 6, is an auxiliary ram or poker 11 which serves to clear the ram of tramp iron or other foreign matter in the coal, and also acts to relieve the strain imposed upon the ram by the packing of the coal in the throat of the retort. This auxiliary ram is directly pivotally connected to rod 7, and a safety link 13, which is designed to break under a predetermined pressure before a dangerous strain is placed upon the mechanism, connects said auxiliary ram to the main ram or box 6, as best shown in Fig. 5. In such figure the link 13 is shown formed

with T'd portions 13a and 13b at the respective ends thereof. The T'd end 13a is adapted to be removably received in a similarly shaped recess 11a in the top of ram 11, while the other end 13b is detachably connected to the ram 6 by engagement with projections 6a and 6b formed interiorly thereof. These projections 6a and 6b may be suitably spaced, as best seen in Fig. 4, 10 to permit certain latitude or lost motion in the connection between the main and auxiliary rams, the object thereof being to cause the auxiliary ram to act in advance of the main ram in the forward movement of the latter to break up the material to be moved by the ram. Accordingly, if an obstacle be encountered by said main ram, or for any other reason the pressure became excessive, said link member will break, thus leaving 15 the main ram stationary, and only the auxiliary ram or poker will continue to reciprocate. The latter being smaller will dislodge the material packed before it and will continue to supply a certain amount of fuel 20 pending replacement of the link.

Associated with the main portion of the grate area is a second reciprocable ram 20, the coal engaging portions 21 of which are hollow, and are thus cooled by the incoming 30 air for the retort as will be hereinafter described.

Located at the lower end of the underfeed portion of the stoker is an overfeed section 25, which may be reciprocated slightly by 35 means of a rod 26, pivoted lever 27, and rod 29, which latter is connected to a bracket 30 depending from such second ram 20. The operation of this overfeed section 25 of the grate area is thus effected at the same 40 time that the ram 20 is operated to supply fuel to the underfeed section of the grate.

Beyond and below this overfeed section 25 of the grate area, is a frame 35, mounted on rollers 36, to which are attached dump 45 grates 37, each tier provided at its lower or rearward end with a knife bar 38 for cutting any clinker that does not fall clear. Each dumping grate is operated by means of a rod 39, and power cylinder 40, and may 50 become a live grate area when necessary, having air ports as is clearly shown in Fig. 1, while, due to its roller support, it may be slid back under the stoker proper with a minimum of power, and at the same time 55 there is no danger of its becoming fouled by clinkers which do not clear or of being burned from the heat in the ash pit, as is apt to occur where such dumping grate is dropped downwardly in order to discharge.

60 There is a main air supply duct 41 (Fig. 2) from which the air is admitted to each section or unit of the apparatus through a separate, damper-controlled air-pipe 42. Each retort, it will be understood is independent of the other in this respect, the space

beneath being partitioned off by vertical plates to form closed chambers 43 into which the pipes 42 respectively lead. The coal fed to the several retorts may accordingly be furnished its proper air for combustion, without depending on or interfering with the air furnished any other retort. From each chamber 43 the air for the overfeed grate sections 25 is admitted through a slideable gate or damper 44, controlled by an external operating handle 45, to a passage 46 leading to such grate sections, the bottom of such passage being formed by a plate 49 and its top by wearing plate 10 and the plate that forms the body of the second ram 20; while the air for the underfeed portion 4 of the grate area is supplied from such air chamber 43 through tuyères 47 that pass around the passage 46 on each side thereof.

70 The operating means for the fuel supplying rams consist of a crankshaft 60, the cranks 8 whereof have heretofore been referred to as being connected with the several rams through rods 7. Gears 61 are keyed to either end of crankshaft 60, and below the latter is a powershaft 62, provided with gears 63 that mesh with such gears 61. The gears 63 and 61 are intermeshed in such manner that the crank for any particular retort will be in advance or behind the next adjacent cranks by 80 a number of degrees equal to 360 divided by the total number of retorts in the stoker. Each connecting rod 7, in addition to being connected with the corresponding ram 6, as has already been described, is provided with 90 a depending arm 66, that operates the upper end of a lever 67, pivotally connected at its lower end to a fixed portion of the frame structure through a second link 68. Through the above means, the crank in addition to 95 driving the ram 6, also drives the ram 20. Lever 67 is pivotally connected at an intermediate point to a block 69 slidably held in a guide 70 that forms the front or free end of a rod 71, the other end of which is attached 100 to bracket 30 on the pusher plate 20 that with projections 21 constitutes such second ram. Said ram 20 is moved to its respective positions through breaking rods 72 screwed into the respective ends of block 69, and having 105 heads 72a adapted to engage with stops 73 in guide 70. A series of removable clips 74, mounted on the rod 71 between the outer stop 73 and the head 72a on the end of the corresponding rod 72 serve to provide for the 110 adjustment of the stroke of the ram. The rods 72 are designed as safety links, and are adapted to break if the ram 20 meets with too 115 great an amount of resistance.

120 The bottom of the frame 80, which carries the overfeed grate 25, comprises a sliding gate or damper 81, for regulating the supply of air to the dump grates 37, the air being supplied through the air passage 46 previously described. This gate or damper 81 125

may be controlled by means of a rod 82 having an exterior handle 83.

From the foregoing, it will be seen that each of the retorts is provided with a separate coal hopper 9 and complete coal supplying means for the grate area in that retort, and similarly, each retort is provided with a separate air supply and separate means for controlling it. In addition to the 10 separate fuel and air supplying means for the retorts, the operation of the fuel supplying means, that is the rams, is effected by entirely separate means, already described, and shown in Fig. 2. The operating means for 15 the various rams include separate crankshafts for each retort so arranged that the pull on the powershaft and on the engine is as uniform as possible.

Other modes of applying the principle of 20 my invention may be employed instead of the one explained, change being made as regards the mechanism herein disclosed, provided the means stated by any of the following claims or the equivalent of such stated means be em- 25 ployed.

I therefore particularly point out and distinctly claim as my invention:—

1. In mechanism of the character described, the combination of a retort, an inclined grate, a fuel supplying ram movably associated with said grate to form the intermediate inclined retort floor therebetween, said ram being open below and a shallow inclined air supply conduit disposed beneath 35 said ram, said conduit being provided with openings in its upper wall allowing air to contact and cool said ram.

2. In mechanism of the character described, the combination of a plurality of retorts, an inclined grate adjacent each of said retorts, an air cooled movable ram mounted adjacent each of said grates and adapted to form the intermediate inclined retort floor therebetween, a shallow inclined air conduit 45 beneath each of said rams for cooling the same, a single power shaft mounted exteriorly of said retorts, a crank-shaft operated by said power shaft, and means connecting said rams with said powershaft, said means producing successive action of said rams.

3. In mechanism of the character described, the combination of a plurality of retorts, an inclined grate adjacent each of said retorts, an air cooled movable ram mounted 55 adjacent each of said grates and adapted to form the intermediate inclined retort floor therebetween, a shallow inclined air conduit beneath each of said rams for cooling the same and means adapted to operate said rams successively, the operation of said rams starting at predetermined angular intervals in the rotation of said powershaft.

4. In mechanism of the character described, the combination of a series of in- 60 dependent retorts, mechanically operated

grates in each of said retorts, a common drive for said grates, adjustable connection between each of said grates and said drive, and separate air supplying means for each of said retorts. 70

5. In mechanism of the character described, the combination of a series of independent retorts, mechanically operated grates in each of said retorts, a common drive for said grates, adjustable connection between each of said grates and said drive, a separate air supplying means connected to each of said retorts, and separate fuel supplying means for each of said retorts. 75

6. In mechanism of the character described, the combination of an inclined underfeed grate, a reciprocable ram adapted to supply fuel at the upper end of said grate, a second reciprocable ram located centrally of said grate adapted to form the intermediate inclined retort floor therewith, and to advance fuel therealong, a shallow inclined air conduit beneath said second ram, and air ports for cooling said last named ram. 80

7. In mechanism of the character described, the combination of an inclined underfeed grate, a reciprocable ram adapted to supply fuel at the upper end of said grate, a second reciprocable ram located centrally of said grate adapted to form the intermediate inclined retort floor therewith, and to advance fuel therealong, said rams being operatively interconnected, a shallow inclined air conduit beneath said second ram, and air ports for cooling said last named ram. 90

8. In mechanism of the character described, the combination of an inclined underfeed grate, a reciprocable ram adapted to supply fuel at the upper end of said grate, a second reciprocable ram located centrally of said grate adapted to form the intermediate inclined retort floor therewith, and to advance fuel therealong, a shallow inclined air conduit beneath said second ram, and an overfeed grate at the lower end of said underfeed grate, and air ports for cooling said last named ram. 105

9. In mechanism of the character described, the combination of an inclined underfeed grate, a reciprocable ram adapted to supply fuel at the upper end of said grate, a second reciprocable ram beneath said grate adapted to form the intermediate inclined retort floor therewith, and to advance fuel therealong, a reciprocable overfeed grate at the lower end of said underfeed grate, said two rams and said overfeed grate being operatively interconnected, an inclined air conduit beneath said second ram for cooling the same and said overfeed grate. 115

Signed by me, this 28th day of December, 1921.

GILBERT WAYNE RUGGLES.
